(57) **CLAIM**

The ornamental design for a grille guard for four wheel vehicle, as shown and described.

DESCRIPTION

FIG. 1 is a perspective view from the front side of a grille guard for four wheel vehicle.

FIG. 2 is a perspective view from the front side thereof.

FIG. 3 is a perspective view from the rear side thereof.

FIG. 4 is a perspective view from the rear side thereof.

FIG. 5 is a front elevation view thereof.

FIG. 6 is a rear elevation view thereof.

FIG. 7 is a left side elevation view thereof.

FIG. 8 is a right side elevation view thereof.

FIG. 9 is a top plan view thereof.

FIG. 10 is a bottom plan view thereof; and,

FIG. 11 is a perspective view thereof shown on a reduced scale and in position of use on the front end of a four wheel vehicle, which is shown in broken lines for illustrative purposes only and forms no part of the claimed design.
